UNITED STATES PATENT OFFICE.

FRANK S. JONES, OF PHILADELPHIA, PENNSYLVANIA.

METAL-CUTTING MACHINE.

Application filed May 6, 1925. Serial No. 28,297.

My invention relates to metal cutting machines for facing slabs.

The usual practice in facing slabs is to rotate the slab at a constant speed and feed the cutting tool toward the axis of rotation. The result is that the linear cutting speed constantly varies and produces inaccurate and non-uniform finish, the maximum cutting speed being when the tool cuts near the periphery of the slab and minimum when the tool cuts near the axis of rotation. In addition to unnecessary loss of time due to the decreasing linear speed much time is lost in removing the finished slab from and placing the unfinished slab on the chuck.

The objects of my present invention are to provide a machine which will face slabs at practically uniform cutting speed; which will have the cutting tool rotating and the chuck stationary to allow an unfaced slab to be mounted on the chuck while the machine is facing another slab; to provide means for quickly moving the chuck to bring an unfaced slab into facing position, and to provide quick traverse mechanism.

These objects, and other advantageous ends which will be described hereinafter, I attain in the following manner, reference being had to the accompanying drawings in which

Figure 1 is a plan view of a machine constructed in accordance with my invention,

Figure 2 a side view of Figure 1,

Figure 3 a left hand end view of Figure 1,

Figure 4 a right hand end view of Figure 1,

Figure 5 an enlarged section on line 5—5 of Figure 1,

Figure 6 an enlarged section on line 6—6 of Figure 5,

Figure 7 a face view of the facing head illustrating the same with certain of the parts removed,

Figure 8 a section on line 8—8 of Figure 7,

Figure 9 a section on line 9—9 of Figure 7,

Figure 10 an enlarged section on line 10—10 of Figure 1,

Figure 11 a section on line 11—11 of Figure 10,

Figure 12 an enlarged section on line 12—12 of Figure 2,

Figure 13 an enlarged section on line 13—13 of Figure 2,

Figure 14 an enlarged section on line 14—14 of Figure 2,

Figure 15 a section on line 15—15 of Figure 14, and

Figure 16 a section on line 16—16 of Figure 6.

Briefly the machine consists of a chuck, for holding a plurality of slabs, movably mounted on a bed so that either slab may be brought into facing position; a rotating facing head having a tool holder movable thereon; mechanism operatively connecting the tool holder with the facing head for feeding the tool holder toward the axis of the head; traversing and reversing mechanism for quickly moving the tool holder on the facing head, and variable speed driving mechanism, for rotating the facing head, operatively connected with the tool holder and facing head so that its speed will be changed when the tool holder moves relatively to the facing head.

Referring to the drawings, the chuck, its mounting and controlling means are constructed as follows: (See Figures 1, 2, 10 and 11.) A chuck block 1 is provided with movable dogs 2 slideable in T-grooves 3 on each of the chuck faces 4. The dogs are moved in the grooves by screws 5 rotatably mounted therein and nuts 6 secured in the grooves by screws or otherwise. Stationary dogs 7 are secured within the grooves opposite the movable dogs 2, by bolts 8. Any number of these dogs may be provided and arranged to meet different requirements. Chuck block 1 is secured to a table 9 rotatably mounted on a saddle 10 slideable on a bed 11. The table is rotatably mounted on saddle 10 preferably by providing a journal 12 on the saddle to fit within a bearing 13 on the table to prevent lateral displacement. The table is provided with a flange 14 which rests on the saddle and has locating holes 15 equally spaced and corresponding in number to the faces 4. These holes co-act with locating means for accurately positioning either of the faces 4 for cutting the slab.

The locating mechanism preferably consists of a spring-pressed plunger 16, normally taking into a locating hole 15, and a lever 17 having one end connected with the plunger and the other end adapted to engage a stop 18 secured to bed 11. When the saddle is slid on bed 11 so that lever 17 engages stop 18, plunger 16 will be withdrawn from hole 15, against the action of the spring and the table

- 2
- may be rotated. The means for rotating the table consists of a spiral gear 19 secured to the table by bolts 20 and meshing with a spiral pinion 21 fixed to a table shaft 22 bearing in the saddle and having a hand wheel 23 thereon outside the saddle. The table may be clamped to the saddle by the usual clamping blocks 24 engaging within an annular groove 25 in the table.
- 10 The means for moving the saddle on the table (see Figures 2, 4 and 12) includes a rack 26 meshing with a pinion 27 fixed to a shaft 28 bearing in a gear housing 29. A rapid traverse hand wheel 30, slidably keyed on the end of shaft 28, is adapted to slide into clutching engagement with a worm wheel 31 meshing with a worm 32 having a slow traverse hand wheel 33 fixed thereto. Rapid traverse hand wheel 30 is moved into clutching engagement with worm wheel 31 by a nut 34 on the end of shaft 28. The nut is preferably provided with handles to facilitate turning. The clutching faces of the hand wheel 30 and worm wheel 31 are preferably V-shaped notches and teeth registering with each other so that they may readily slide out of engagement when the hand wheel is moved in either direction for rapidly moving the saddle.
- 30 The tool, for facing the slabs which are held in position by the chuck, rotates and at the same time moves toward its axis of rotation. The means for rotating the tool (see Figures 2, 3, 4 and 5) includes a facing head 35 fixed to a hollow spindle 36 rotatably mounted in bearings 37 on the bed. A gear 38 is fixed to the spindle between the bearings and meshes with a pinion 39 on a drive shaft 40 mounted in bearings 41.
- 40 Variable speed driving mechanism 42, coupled with the drive shaft, may be of any suitable type but is preferably of the type shown known as a hydraulic variable speed gear. This variable speed driving gear includes units 43 and 44. Unit 43 is coupled with the drive shaft 40 and unit 44 with a motor 45. The principle upon which this variable speed gear operates is to pump oil from unit 44 through pipe 46 to drive unit 43, which in turn will drive the shaft 40. The amount of oil pumped is governed by a control shaft 47 which is operatively connected with the mechanism for rotating and moving the tool toward its axis of rotation.
- 55 The means for moving the tool toward its axis of rotation (see Figures 1, 5 and 6) includes a tool holder 48 slidable on facing head 35 toward its axis of rotation. A feed screw 49 rotatably mounted in head 35 is connected with a feed nut 50 secured to tool holder 48. A gear 51 keyed to the screw meshes with a gear 52 on a feed shaft 53 rotatably mounted in head 35 and having a keyed bevel gear 54 meshing with a bevel gear 55 on a hollow shaft 56 rotatably mounted in and passing through hollow spindle 36. A friction gear 57 fixed to the hollow shaft meshes with a gear 58 fixed to a counter-shaft 59 rotatably mounted on the bed. Clutching mechanism 60 operatively connects counter-shaft 59 with spindle 36 through a clutching shoe 61, keyed to shaft 59, adapted to spring into clutching engagement with the inner face 62 of a drum gear 63 meshing with a gear 64 fixed to spindle 36. Gear 64 and drum 62 are of a different ratio from gears 57 and 58. The result is that when the spindle and facing head rotate at one speed, hollow shaft 56 will be driven at another speed. The difference in the speeds is the rate at which tool holder 48 is fed toward its axis of rotation. Shoe 61 is sprung into engagement with face 62 of gear 63 by the action of cams 65 disposed between wearing blocks 66 and pivotally connected thereto by flanges 67 journaled in opposed recesses 68 (see Figures 13, 14 and 15). The cams are actuated by collar 71, freely mounted on shaft 59, being forced between adjustable buttons 70 mounted in the outer ends of arms 69 which are integral with cams 65. It is evident that, as collar 71 moves buttons 70 away from shaft 59, arms 69 will rotate the cams 65, separate the members of each pair of wearing blocks 66 and bring shoes 61 into engagement with face 62 of gear 63. A yoke 72, having its ends engaging in an annular groove 73 in collar 71, is pivoted at 74 in bed 11 and has an arm 75 connected with a control lever 76 by a rod 77. As collar 71 is moved toward shoe 61 to separate arms 69, there is a tendency to force the ends of arms 69 toward shoe 61. To prevent this canting of the arms, I provide faces 78 on shoe 61 adjacent the ends of the arms 69 against which the arms bear.
- To centrifugally balance tool holder 48, I provide a pair of counter-weights 79 (see Figures 7, 8 and 9), slidable in head 35 in the opposite direction to tool holder 48. The counter-weights are operatively connected with the feed screw so that, as the tool holder moves in one direction relatively to the axis of rotation, the counter-weights will move in the opposite direction. The means for imparting this movement to the counter-weights includes counter-weight screws 80 rotatable in the head and having gears 81 meshing with idler 82 which in turn mesh with gear 52 on feed shaft 53. I preferably provide cover plates 83 over the counter-weights to prevent chips from falling between the moving parts.
- The mechanism for rotating control shaft 47, (see Figures 1, 3, 4, 5 and 6) to cause facing head 35 to increase its speed as tool holder 48 moves toward its axis of rotation, includes a telescoping shaft 84 having one end fastened, preferably at 85, so that it

rotates with the spindle and the other end provided with a screw 86 engaging with a nut 87, integral with friction gear 57, so that the nut rotates at the same speed as 5 hollow shaft 56 which actuates the tool holder. It will be seen that by fastening screw 86 so that it will rotate at the speed of spindle 36 and fastening nut 87 so that it will rotate at the speed of feed shaft 56, the difference between the speeds will determine the rate of speed at which nut 87 will rotate about screw 86 and cause it to move lengthwise. This difference in speeds of shaft 56 and spindle 36, as previously 10 described, results from the arrangement of gears 57, 58, 63 and 64. This lengthwise movement of screw 86 to control shaft 47 is transmitted through a rack 88 rotatably connected to the end of screw 86 and slidably 15 mounted in a bracket 89. A gear 90, meshing with rack 88, is keyed to an extension shaft 91 geared to control shaft 47 by bevel gears 92 and 93. This control shaft 47 may be directly connected with the rack 88 by 20 directly connecting units 43 and 44 and extending the rack slightly to meet the control shaft.

The quick traverse mechanism for quickly moving tool holder 48 in either direction includes a pulley 94, (see Figures 5 and 6) 25 on drive shaft 40, connected by a belt with a pulley 95 on a quick traverse shaft 96 having one end bearing in a bracket on bed 11 and the other end in a gear box 97 which 30 houses the clutching and reversing mechanism for operatively connecting the shaft with the tool holder. The clutching and reversing mechanism includes a clutching member 98, slidably keyed on shaft 96, 35 adapted to engage a clutching face on either bevel gear 99 or 100 fixed to sleeves 101 and 102 journaled in the gear box and having shaft 96 bearing therein. A bevel gear 103 meshes with bevel gears 99 40 and 100 and is keyed to a stud shaft 104 having a hand wheel 105 fixed thereto outside of the gear box. A hollow controlling shaft 106 has one end keyed to sleeve 101 as shown at 107 and the other end keyed to 45 a gear 108 meshing with a gear 109 keyed to shaft 59. By moving clutching member 98 into engagement with either of the clutching faces on bevel gears 99 or 100 a forward or reverse movement will be transmitted 50 from drive shaft 40, through pulleys 94 and 95, and quick traverse shaft 96 to hollow controlling shaft 106, gears 108 and 109 and counter-shaft 59 which is operatively connected with the tool holder. When this 55 quick traverse movement is being transmitted to the tool holder, clutching mechanism 60 is manipulated to disconnect shaft 59 from spindle 36. Clutching member 98 is moved by a yoke 110, (see Figure 16) 60 pivoted in the gear box at 111 and having a control lever 112 fixed thereto. With clutching member 98 in neutral position, tool holder 48 may be moved in either direction by manipulating hand wheel 105 which is disposed adjacent the facing head so that 70 the position of the tool holder may be readily seen while in motion.

To insert a slab in the chuck, screws 5 are manipulated so that dogs 2 and 7 will hold the slab in position. The slab is then 75 brought into facing position adjacent the rotating tool by manipulating hand wheel 30. If a finer adjustment of the slab is necessary, nut 34 is turned until the notched clutching face of hand wheel 30 engages the notched 80 clutching face on worm 31. Hand wheel 33 is then manipulated to obtain the finer adjustment. After the slab is adjusted in proper facing position, lever 76 is moved to actuate clutch 60 to operatively connect the rotating 85 spindle with shaft 59 which is operatively connected with the tool holder. As the tool holder rotates it will be fed toward its axis of rotation. This feeding movement is transmitted to the tool holder from spindle 90 36 through gears 64 and 63, clutch 60, shaft 59, gear 58, friction gear 57, hollow shaft 56, bevel gears 55 and 54, feed shaft 53, gears 52 and 51, screw 49 and nut 50 to the tool 95 holder 48. As the tool holder is fed toward its axis of rotation, the speed of the facing head 35 is increased so that the linear cutting speed of the tool will be practically constant throughout its entire cutting cycle. This change in speed of head 35 is caused by 100 a rotation of control shaft 47 which governs the hydraulic variable speed gear 44. The movement to control shaft 47 is transmitted from screw 86, which rotates at the same speed as the facing head, and nut 87 which 105 rotates at the same speed as hollow shaft 56 which feeds the tool holder. The difference in speeds of screw 86 and nut 87 causes the screw to move lengthwise. This lengthwise movement is transmitted and transformed 110 into rotary movement through rack 88, gear 90, shaft 91 and bevel gears 92 and 93 to control shaft 47. Spindle 36 transmits rotary movement to tool holder 48 through facing head 35, and radial movement 115 through gears 64, clutch 60, shaft 59, gears 58 and 57, shaft 56, bevel gears 55 and 54, feed shaft 53, feed screw 49 and nut 50 so that spindle 36 and hollow shaft 56 transmit a lengthwise movement to screw 86 which 120 actuates control shaft 47 and causes the rotating speed of the tool holder to increase as it approaches its axis of rotation. After the slab has been faced, clutch 60 is disconnected and lever 112 manipulated to connect 125 the quick traversing mechanism to bring the tool holder to its former position. While one slab is being faced, another slab is set on the chuck to be ready for facing when the previous slab is finished. The chuck is then 130

5 moved away from the tool by unscrewing nut 34 and manipulating wheel 30 until lever 17 engages stop 18 to withdraw plunger 16 from hole 15. The chuck is then
 10 turned by manipulating hand wheel 23 until another hole 15 is in registry with plunger 16 and the new slab is facing the tool. The chuck is then brought toward the tool by manipulating hand wheel 30. During
 15 this movement lever 17 will leave stop 18 and spring-pressed plunger 16 will move into a hole 15 to accurately position the slab relatively to the tool. The slab is then adjusted toward the tool as previously described.

20 Much time is saved in facing slabs with a machine such as above described because the cutting speed of the tool may be set at a maximum and maintained at that speed throughout its cutting cycle, and because the chuck is provided with a plurality of faces for allowing one slab to be set while another is being cut.

25 While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

30 Having thus described my invention, what I claim as new and desire to secure by Letters Patent is:—

35 1. In a metal cutting machine having a bed, a facing head rotatable in the bed and a tool holder movable on the head; a work carrier including a saddle mounted on the bed, a journal formed on the saddle, a table rotatably mounted on the saddle, a bearing formed in the table and engaging the journal, a flange formed on the table and bearing on the saddle, a plural faced chuck fixed on the table, and means for moving the work carrier toward and from the head.

40 2. In a metal cutting machine having a bed, a facing head rotatable in the bed and a tool holder movable on the head; a work carrier including a saddle mounted on the bed, a journal formed on the saddle, a table rotatably mounted on the saddle, a bearing formed in the table and engaging the journal, a flange formed on the table and bearing on the saddle, a plural faced chuck fixed on the table, and means for moving the work carrier toward and from the head at high and low speed.

45 3. In a metal cutting machine having a bed, a facing head rotatable in the bed and a tool holder movable on the head; a work carrier including a saddle mounted on the bed, a journal formed on the saddle, a table rotatably mounted on the saddle, a bearing formed in the table and engaging the jour-

50 nal, a flange formed on the table and bearing on the saddle, a plural faced chuck fixed on the table, means to rotate the table, and means for moving the work carrier toward and from the head.

55 4. In a metal cutting machine having a bed, a facing head rotatable in the bed and a tool holder movable on the head; a work carrier including a saddle mounted on the bed, a journal formed on the saddle, a table rotatably mounted on the saddle, a bearing formed in the table and engaging the journal, a flange formed on the table and bearing on the saddle, means for locking the table in selected positions, a plural faced chuck fixed on the table, means to rotate the table, and means for moving the work carrier toward and from the head.

60 5. In a metal cutting machine having a bed, a facing head rotatable in the bed and a tool holder movable on the head; a work carrier including a saddle mounted on the bed, a table rotatably mounted on the saddle, a plural faced chuck on the table, a spiral gear on the table, a shaft rotatably mounted in the saddle and having a pinion meshing with the spiral gear for rotating the table, means for locking the table in selected positions, and means for moving the work carrier toward and from the head.

65 6. In a metal cutting machine having a bed, a facing head rotatable in the bed and a tool holder movable on the head; a work carrier including a saddle mounted on the bed, a table rotatably mounted on the saddle, a spring pressed dog for locking the table in selected positions, a plural faced chuck on the table, means for moving the work carrier toward and from the head, and a lever adapted to engage the dog and release the table.

70 7. A metal cutting machine including a bed; a chuck movable on the bed; a spindle rotatable in the bed; a facing head fixed to the spindle; means for rotating the spindle; a tool holder movable on the head; a feed nut on the tool holder; a feed screw threaded through the nut and rotatable in the head for moving the tool holder; a gear on the feed screw; a feed shaft rotatable in the head; a gear fixed on the feed shaft and meshing with a gear on the screw; a hollow shaft rotatable in the spindle and operatively connected with the feed shaft, and means operatively connected with the spindle for rotating the hollow shaft.

75 8. A metal cutting machine including a bed; a chuck movable on the bed; a spindle rotatable in the bed; a facing head fixed to the spindle; means for rotating the spindle; a tool holder movable on the head; a feed nut on the tool holder; a feed screw threaded through the nut and rotatable in the head for moving the tool holder; a gear on the

operatively connected with the rack for changing the speed of the driving mechanism as the shaft moves lengthwise.

17. A metal cutting machine including a bed; a chuck movable on the bed; a spindle rotatable in the bed; a facing head fixed to the spindle; a tool holder movable on the head; means operatively connected to the spindle for moving the tool holder; a drive shaft operatively connected with the spindle; a quick traverse shaft operatively connected with the drive shaft; a controlling shaft operatively connected with the tool holder, and reversing means operatively connected with the controlling shaft and the quick traverse shaft.

18. A metal cutting machine including a

bed; a chuck movable on the bed; a spindle rotatable in the bed; a facing head fixed to the spindle; a tool holder movable on the head; means operatively connected to the spindle for moving the tool holder; a drive shaft operatively connected with the spindle; a hollow controlling shaft having one end operatively connected with the tool holder; reversing mechanism operatively connected with the other end, and a quick traverse shaft within the controlling shaft operatively connected with the reversing means and the drive shaft.

In testimony whereof I have signed my name to this specification.

FRANK S. JONES.
